G. R. DAVIS

Des. 146,643

SCARF OR SIMILAR ARTICLE

Filed Jan. 22, 1947

GLADYS ROCKMORE DAVIS,
INVENTOR,

BY Victor M. Helfand

ATTORNEY

UNITED STATES PATENT OFFICE

146,643

DESIGN FOR A SCARF OR SIMILAR ARTICLE

Gladys Rockmore Davis, New York, N. Y.

Application January 22, 1947, Serial No. 136,291

Term of patent 3½ years

(Cl. D3—12)

To all whom it may concern:

Be it known that I, Gladys Rockmore Davis, a citizen of the United States of America, residing in New York, county of New York, and State of New York, have invented a new, original, and ornamental Design for a Scarf or Similar Article, of which the following is a specification, reference being had to the accompanying drawing, forming part thereof wherein the figure is a plan view of a scarf showing my new design.

I claim:

The ornamental design for a scarf or similar article, substantially as shown.

GLADYS ROCKMORE DAVIS.
